DRIVING MECHANISM FOR LAUNDRY MACHINERY

Lloyd L. Poland, Boston, Mass.

Application September 13, 1948, Serial No. 48,993

5 Claims. (Cl. 74—218)

1

This invention relates to mechanism for driving a rotatable driven member and embodies shifting means operative automatically to change the direction of rotation of the driven member periodically after a few revolutions in each direction.

The mechanism of the present invention is especially adapted for driving the rotatable drum which is an essential part of many types of laundry machinery and similar apparatus used by laundries for washing clothes, dry-cleaning garments, etc. This type of machinery comprises a receptacle adapted to hold a cleaning fluid, such as a soap solution, a hydrocarbon solvent, etc. A perforated cylindrical drum adapted to receive articles to be cleansed is supported for rotation within the receptacle. The inner surface of the drum usually is provided with a plurality of ribs which tend to carry the articles being cleansed with the drum a part of a revolution and then release them. The direction of rotation of the drum usually is reversed after every three or four revolutions to facilitate the cleaning action.

It has been common practice to employ an expensive reversing electric motor with control apparatus for driving the drum and reversing its direction of rotation. This usually requires three phase current which is not available for many desired installations. So far as I am aware no other means has been proposed for this purpose which is entirely satisfactory and can be manufactured at a cost sufficiently low to warrant its use.

The present invention contemplates a low cost mechanism suitable for this purpose which is adapted to receive and transmit power from any desired source, such as a low cost electric motor or an overhead power shaft.

The invention will be more clearly understood from the following description in conjunction with the accompanying drawings, in which:

Fig. 1 is a rear longitudinal elevational view of a laundry machine embodying the invention;

Fig. 2 is an end elevational view of the same partly broken away;

Fig. 3 is a detail sectional view taken upon the line 3—3 of Fig. 2;

Fig. 4 is a somewhat diagrammatic rear longitudinal elevational view of a portion of the machine;

Figs. 5 and 6 are sectional views taken upon the line 5—5 of Fig. 1 and showing the parts in different positions; and

Fig. 7 is an enlarged sectional view taken upon the line 7—7 of Fig. 6.

2

The machine illustrated in the accompanying drawings comprises a frame 10 in which is supported a stationary receptacle 11 adapted to contain a cleaning fluid, such as a soap solution, a hydrocarbon solvent, etc. A perforated drum 12 adapted to receive articles to be cleansed is supported for rotation within the receptacle 11. For this purpose, the opposite ends of the drum are suitably secured to the adjacent ends of aligned shafts 13 and 14 which extend through the ends of the receptacle 11 and are rotatably mounted in bearings in frame 10. A pulley 15 is fixed upon each of the shafts 13 and 14 near their outer ends. A shaft 16 is rotatably mounted in bearings in frame 10 and has a pulley 17 fixed thereto near each end. Belts 18 operatively connect the pulleys 15 and 17.

A pair of spaced pulleys 20 and 21 are supported upon shaft 16 for rotation relative thereto. A pulley 23 is fixed upon shaft 16 and is positioned between pulleys 20 and 21 with its peripheral surface substantially continuous with that of each of the pulleys 20 and 21. The pulley 20 is rotated continuously in one direction by any suitable means, such as by an electric motor M through a belt 24.

A pair of rods 26 and 27 spaced transversely of the machine (Figs. 1, 2, 5 and 6) are supported in fixed parallel relation by the frame 10. The rods 26 and 27 slidably support a carrier C forming part of a shifting mechanism for changing the direction of rotation of pulley 23 automatically for desired intervals. The carrier C comprises a main supporting member 30 extending between the rods 26 and 27 and having bearing surfaces adapted for sliding engagement with the rods. One end of each of a pair of spaced rods 31 and 32 is fixed in the member 30. A shaft 33 extends between and is slidably supported upon the other end portions of the rods 31 and 32. As illustrated, the shaft 33 is provided with an opening 34 (Fig. 7) through which the rods 31 and 32 project. The shaft 33 normally is held against stops 36 and 37 fixed upon the rods 31 and 32 respectively by springs 38 and 39 surrounding the rods and extending between the shaft and member 30. A pair of idler pulleys 41 and 42 are rotatably supported in spaced relation upon shaft 33. An endless belt 43 operatively connects pulleys 20, 21, 41 and 42 in driving relation at all times and is arranged so that pulley 21 is rotated in a direction opposite to that of pulley 20.

Suitable mechanism is provided for reciprocating the carrier C at a desired rate. A suitable mechanism for this purpose may comprise a worm

wheel 45 fixed upon a stud shaft 46 mounted in bearings carried by the frame 10. The worm wheel 45 is engaged by a worm 44 rotatably mounted upon shaft 16 and having a driving connection with the hub of pulley 21. One end of an L-shaped bar 47 is secured to the member 30. A cam follower 48 is fixed in the bar 47 near its other end and engages a cam groove 49 in the rear face of a disc 50 fixed upon the shaft 46. The cam groove has two diametrically opposite circular portions 51 and 52 each extending about 150 angular degrees. The portions 51 and 52 are connected by inclined groove portions 53 and 54. When the cam follower 48 engages the portion 51 the carrier C is held at one end of its path of movement and when the follower 48 engages the portion 52 the carrier is held at the opposite end of its path of movement. Engagement of the follower 48 with the portions 53 and 54 causes the carrier C to be moved from one end of its path of movement to the other. The arrangement is such that the cam disc 50 rotates once for about every eight revolutions of the drum 12.

The motor M is adapted to supply the necessary power to operate the machine. Thus, by energizing the motor, power is transmitted through the belt 24 to rotate the pulley 20 continuously in one direction. Power is transmitted through the belt 43 to rotate the pulley 21 continuously in a direction opposite to the direction of rotation of pulley 20 at all times. Rotation of the pulley 21 is transmitted through the worm 44 and worm wheel 45 to cause continuous rotation of the cam disc 50. Assuming that the cam follower 48 is positioned in the circular portion 51 of the cam groove 49 and the cam disc 50 is rotating in the direction indicated by the arrow in Fig. 3, the carrier C will be positioned at one end of its path of movement as indicated in dotted lines in Fig. 4. When the cam disc 50 has rotated to a position such that the cam follower 48 enters the inclined cam groove portion 53, the carrier C is moved from its dotted line position shown in Fig. 4 to its full line position, or opposite end of its path of movement. When the carrier C is in its full line position indicated in Fig. 4, the cam follower 48 is positioned in the circular portion 52 of the cam groove 49. As rotation of the cam disc 50 continues and the cam follower 48 enters the inclined portion 54 of the cam groove 49, the carrier C is moved from its full line position back to its dotted line position shown in Fig. 4.

The movement of the carrier C from one end of its path of movement to the other causes the idler pulleys 41 and 42 to be moved bodily in the same direction and shifts the position of the belt 43 with respect to the pulleys 20, 21 and 23. Thus, when the carrier C is in the full line position shown in Fig. 4, one portion of the belt 43 overlaps and engages both of the pulleys 20 and 23 while the portion of the belt 43 engaging the pulley 21 is out of engagement with the pulley 23 as indicated in full lines in Fig. 4. When the belt 43 is thus positioned, the pulley 23 is driven in the same direction as pulley 20 and power is transmitted to rotate the drum 12 clockwise as viewed from the right of Fig. 1. This rotation of the drum 12 continues so long as the cam follower 48 engages the circular portion 52 of the cam groove 49, that is, for about 3 to 4 revolutions of the drum. It will be noted that under these conditions of operation, the springs 31 and 32 permit the shaft 33 to tilt slightly as indicated in Fig. 5 thus taking up slack in belt 43.

When the carrier C is moved from its full line

position to its dotted line position shown in Fig. 4, the portion of the belt 43 engaging pulley 20 is moved out of engagement with pulley 23 and the portion engaging pulley 21 is shifted to overlap and engage both the pulleys 21 and 23 as indicated in dotted lines in Fig. 4. When the belt 43 is thus positioned, the pulley 23 is driven in the same direction as pulley 21 and power is transmitted to rotate the drum 12 counterclockwise as viewed from the right of Fig. 1. Rotation of the drum in this direction continues so long as the cam follower 48 engages the circular portion 51 of the cam groove 49, that is, about 3 to 4 revolutions. It will be noted that under these conditions of operation, the springs 31 and 32 permit the shaft 33 to tilt slightly as indicated in Fig. 6, thus taking up slack in belt 43.

I claim:

1. In combination, a pair of spaced driving pulleys, a driven pulley positioned between said driving pulleys and forming therewith a substantially continuous surface, a pair of spaced idler pulleys supported for movement bodily in a path spaced from said driving pulleys and parallel to the axes thereof, the axes of said idler pulleys being substantially perpendicular to the axes of the driving pulleys, an endless belt providing an operative driving connection between said driving and idler pulleys and alternately engaging a driving and idler pulley to rotate said driving pulleys in opposite directions, and means for reciprocating the idler pulleys along said path to connect said driven pulley alternately in driving relation with each driving pulley while maintaining an operative driving connection between all of the driving and idler pulleys.

2. In combination, a driven shaft, a first pair of idler pulleys mounted in spaced relation upon said shaft for independent rotation relative thereto, a pulley fixed to said shaft and positioned between said pair of idler pulleys and forming with the latter a substantially continuous surface, a carrier mounted for movement in a path spaced from said pulleys and parallel to said shaft, means for supporting a second pair of idler pulleys upon said carrier for movement therewith with their axes substantially perpendicular to the axes of the first pair of idler pulleys, an endless belt providing an operative driving connection between all the pulleys of said first and second pairs and alternately engaging a pulley of said first and second pairs to rotate the pulleys of said first pair in opposite directions, means for reciprocating said carrier to cause said belt to connect said fixed pulley alternately in driving relation with each pulley of said first pair while maintaining an operative driving connection between all the pulleys of said first and second pairs, and driving means for moving said endless belt longitudinally.

3. In combination, a driven shaft, a first pair of idler pulleys mounted in spaced relation upon said shaft for independent rotation relative thereto, a pulley fixed to said shaft and positioned between said pair of idler pulleys and forming with the latter a substantially continuous surface, a carrier mounted for movement in a path spaced from said pulleys and parallel to said shaft, means for supporting a second pair of idler pulleys upon said carrier for movement therewith with their axes substantially perpendicular to the axes of the first pair of idler pulleys, an endless belt providing an operative driving connection between all the pulleys of said first and second pairs and alternately engaging a pulley of

said first and second pairs to rotate the pulleys of said first pair in opposite directions, means for reciprocating said carrier to cause said belt to connect said fixed pulley alternately in driving relation with each pulley of said first pair while maintaining an operative driving connection between all the pulleys of said first and second pairs, said supporting means including means for automatically changing the positions of the pulleys of said second pair in response to changes in tension upon different portions of said belt as said carrier is moved into its different functional positions, and driving means for moving said endless belt longitudinally.

4. In combination, a driven shaft, a first pair of idler pulleys mounted in spaced relation upon said shaft for independent rotation relative thereto, a pulley fixed to said shaft and positioned between said pair of idler pulleys and forming with the latter a substantially continuous surface, a carrier mounted for movement in a path spaced from said pulleys and parallel to said shaft, means for supporting a second pair of idler pulleys upon said carrier for movement therewith with their axes substantially perpendicular to the axes of the first pair of idler pulleys, an endless belt providing an operative driving connection between all the pulleys of said first and second pairs and alternately engaging a pulley of said first and second pairs to rotate the pulleys of said first pair in opposite directions, means actuated by the rotation of one of the pulleys of said first pair for reciprocating said carrier to cause said belt to connect said fixed pulley alternately in driving relation with each pulley of said first pair while maintaining an operative driving connection between all the pulleys of said first and second pairs, and means for moving said endless belt longitudinally.

5. In combination, a pair of rotatable idler 40

members, a rotatable driven member positioned between said idler members, a carrier, means for supporting said carrier for reciprocating movement in a path spaced from said idler members 5 and said driven member and parallel to their axes of rotation, mechanism operatively engaging said idler members whereby rotation of one idler member causes rotation of the other idler member in the opposite direction, each of the 10 portions of said mechanism engaging said idler members being slidably thereon for simultaneous movement in the same direction whereby either of said portions may be moved into driving engagement with said driven member while the other of said portions is moved out of engagement with said driven member and maintain both of said portions in driving engagement with said idler members, said mechanism also having a portion thereof supported upon said carrier for 15 rotation and for reciprocating movement therewith in said path and being adapted when so reciprocated to effect said shifting of said mechanism into and out of driving engagement with said driven member, separate means for rotating 20 one of said pair of idler members in one direction, and means for reciprocating said carrier.
